UNITED STATES PATENT OFFICE.

BENJAMIN FRANKLIN HACKETT AND JOHN J. OWEN, OF WILLARD, TERRITORY OF NEW MEXICO.

TRACK-ADJUSTING JACK.

968,150.

Specification of Letters Patent. Patented Aug. 23, 1910.

Application filed May 6, 1909. Serial No. 494,267.

To all whom it may concern:

Be it known that we, BENJAMIN F. HACKETT and JOHN J. OWEN, citizens of the United States, residing at Willard, in 5 the county of Torrance and Territory of New Mexico, have invented certain new and useful Improvements in Track-Adjusting Jacks; and we do declare the following to be a full, clear, and exact description of 10 the invention, such as will enable others skilled in the art to which it appertains to make and use the same.

This invention relates to improvements in track alining and lifting jacks.

15 The object of the invention is to provide a jack of this character by means of which track rails may be brought into proper alinement or gage and by means of which the rails may be lifted to the proper grade 20 or level.

With the foregoing and other objects in view, the invention consists of certain novel features of construction, combination and arrangement of parts, as will be more fully 25 described and particularly pointed out in the appended claims.

In the accompanying drawings, Figure 1 is a longitudinal sectional view of a jack 30 constructed in accordance with the invention; showing the same engaged with a track rail for the purpose of alining the same; Fig. 2 is a top plan view of the same; Fig. 3 is a side view, showing the manner of using the jack for lifting a rail; Fig. 4 is a detail perspective view of the detachable evening block for the foot piece of the 35 jack.

Referring more particularly to the drawings, 1 denotes the body portion of the jack 40 in which is formed a guide channel 2 to receive the adjustable operating bar 3. On one end of the body portion 1 is formed an obliquely disposed wedge shaped foot piece 4, one end of which has formed thereon an 45 anvil 5 whereby the opposite end may be driven into the ground to form a stop or abutment against which pressure is applied when the jack is operated. The foot piece 4 is provided on one side with a rail engaging plate 6, the purpose of which will 50 hereinafter appear.

On the inner end of the adjustable operating bar 3 is formed a stop lug 7, while on the outer end of the same is secured a rail 55 engaging head 8 which is preferably round-

ed on its outer end, as shown, to fit between the base flange and head of the rail when applied thereto. On the outer side of the operating bar 3 is formed a series of ratchet teeth 9 which are adapted to be engaged by 60 operating pawls 10 and 11 pivotally mounted in the bifurcated head 12 of an operating lever 13, said lever being preferably detachably engaged with the head 12 by means of a socket 14 formed on the head, as shown. 65 The head 12 is pivotally mounted in apertured ears 15 formed on each edge of the open side of the body portion 1 whereby the pawls 10 and 11 carried by the head will work in the channel 2 and operatively engage the ratchet teeth 9 of the operating bar to project the same outwardly. The pawl 11 has formed on its outer end an inwardly projecting hook 16 which engages the teeth 9 of the bar 3 so that when the 70 operating lever and head are swung in one direction, the hook on the pawl 11 will engage the teeth 9 and when the lever and head are swung in the opposite direction, the pawl 10 will operatively engage the 75 teeth 9 so that the operating bar 3 is projected forwardly at each movement of the lever.

In using the device for alining a track rail, the head 8 is engaged with the rail and 80 the foot piece driven into the ground thus forming a brace, after which the operating lever is actuated to engage the pawls with the operating bar, thus projecting the same, as hereinbefore described, and forcing the 85 rail into alinement.

When the jack is employed for lifting a rail, an evening piece 17 is provided and engaged with the anvil end 5 of the foot piece 90 so that when the jack is stood up in position to engage the plate 6, with the underside of the rail to be raised, the piece 17 will support the outer end of the foot piece in proper position and will act as a fulcrum on which the jack may be rocked in the operation of lifting the track. If desired, the 95 pawls 10 and 11 may be provided with suitable handles 18 for disengaging the same from the teeth of the operating bar. The body portion of the jack may be also provided with a handle 19 by means of which 100 the same may be more readily carried.

It will be noticed that as the foot piece 4 is secured on the body 1 obliquely, that the 105 jack will not assume a vertical position when 110

resting on the foot and therefore the evener piece 17 is provided for engagement with the anvil end of the foot so that when the head 8 is placed under an object to be lifted 5 the rack bar 3 will stand vertically and the device rest on an even keel so to speak. The evener piece 17 is only used when the jack is employed as in Fig. 3, (as a fulcrum piece), and when it is placed under some 10 object to be lifted.

From the foregoing description, taken in connection with the accompanying drawings, the construction and operation of the invention will be readily understood without requiring a more extended explanation. 15

Various changes in the form, proportion and the minor details of construction may be resorted to without departing from the principle or sacrificing any of the advantages of the invention, as defined in the appended claims. 20

Having thus described our invention, what we claim is:

1. In a jack of the character described, a 25 body portion having formed therein a guide

channel, an operating bar slidably mounted in said channel, a head on the outer end of said bar, means to project the latter, an oblique foot piece on one end of said body portion adapted to be driven into the ground to form an anchoring brace, a rail engaging plate on said foot piece, and an evening block adapted to be detachably engaged with said foot piece to hold the jack in an upright position. 30

2. In a lifting jack, a body, an operating bar slidably mounted therein, means for projecting the same from one end of the body, an oblique bracing foot on the opposite end of the body and an evener block detachably engaged with the foot to hold the jack in upright position. 40

In testimony whereof we have hereunto set our hands in presence of two subscribing witnesses.

BENJAMIN FRANKLIN HACKETT.
JOHN J. OWEN.
